UNITED STATES PATENT OFFICE.

WILLIAM H. ROSE, OF BALTIMORE, MARYLAND, AND JAMES A. WATSON, OF WASHINGTON, DISTRICT OF COLUMBIA, ASSIGNEES TO THE MARINE TORCH COMPANY OF BALTIMORE CITY, OF BALTIMORE, MARYLAND.

MARINE TORCH.

SPECIFICATION forming part of Letters Patent No. 740,317, dated September 29, 1903.
Application filed January 25, 1903. Serial No. 91,250. (No model.)

To all whom it may concern:

Be it known that we, WILLIAM H. ROSE, residing at the city of Baltimore, State of Maryland, and JAMES A. WATSON, residing at Washington, in the District of Columbia, citizens of the United States, have invented certain new and useful Improvements in Marine Torches, of which the following is a specification.

This invention consists in means for storing a buoyant torch on the bottom of a harbor or waterway and means for releasing the torch at will, so that it may float to the surface to illuminate any objects in the vicinity, the torch being one of that class which will automatically ignite in contact with water.

In the accompanying drawings, Figure 1 is a central sectional view of a torch and the casing within which it is hermetically sealed. Fig. 2 is a plan view of the top plate of the casing, and Fig. 3 is a view illustrating the action of the torch.

The torch *a* is of that class described in Letters Patent No. 647,610, issued to Rose and Holmes on April 17, 1900. The characteristics of these torches are that when placed in water they will float and the water will enter through certain orifices and coming in contact with carbide of calcium will produce acetylene gas, which issues from burners at the upper part of the torch. These torches are also provided with a chemical igniter, preferably phosphid of calcium, which in the presence of water will produce a flame to ignite the acetylene gas.

The particular torch *a* illustrated in the drawings is not claimed herein, as it forms the subject of a copending application filed by William H. Rose. This torch may be briefly described as follows:

The torch *a* consists of a hollow cylinder 1, having a top plate 2, in which are gas-burners 3. At the bottom of the torch is a phosphid-chamber 4, having a small opening at its bottom to admit water and having an outlet-tube 5, the upper end of which is adjacent to the burners 3. The chamber 4 is preferably charged with lumps of phosphid of calcium. Surrounding the chamber 4 is a quantity of carbide of calcium, preferably in the form of lumps 6. A perforated dia-

phragm 7 is provided to prevent the carbide from getting into the upper part of the torch, and perforations 8 are provided to admit water to the carbide when the torch is afloat. The larger part of the shell 1 is empty, rendering it buoyant, as shown in Fig. 3.

It is sometimes desirable to light up a selected part or parts of a harbor or waterway, as in the case of the presence of an enemy's vessel at night, and it is the purpose of this invention to supply a convenient and effective device for this class of illumination. To this end the torch *a* is normally contained within a sealed can or casing *b*. The casing *b* is preferably cylindrical, as is the torch, and provided with a weighted bottom 9 to cause it to stand or float upright in the water. The device is preferably provided with an anchor 10 to retain the casing at the place where the torch is desired to operate. The torch is stored within the casing, as shown, and connected to the casing by a cord or chain 11 to anchor the torch and prevent it from drifting away when released.

Means are provided for automatically opening the casing to release the torch. A variety of devices might be suggested for accomplishing this object. The device in the drawings is constructed as follows: A strong plate 12 fits within the upper end of the casing and rests upon a shoulder 13. Above the plate 12 is a stout cap-plate 14, having a series of projections 15, which fit within holes 16 in the plate 12, and also a circular rib 17, which interlocks with ribs 18 and 19 on the plate 12. Between the plates 12 and 14 is a chamber 20, containing gunpowder or other explosive material. A cable 21 extends from the chamber 20 to a convenient point on shore or on shipboard, said cable containing conductors through which a current may be sent to ignite the explosive in the chamber 20. In order to protect the connection of the cable to the cap and also to permit the casing to stand or float upright in the water, the cable is brought down to the bottom of the casing and connected to it by suitable clips 22. The joint between the cable and the cap is of course water-tight. The joint between the cap and the casing is covered by a ring of 100

thin soft tin or other metal 23, which is joined to the cap and to the casing by solder or otherwise in such manner as to close the casing absolutely against the entrance of water.

5 The interlocking of the ribs 18 and 19 with rib 17 and of the projections 15 with the opening 16 prevents the pressure of the gases produced by the explosion in the chamber 20 from injuriously affecting the torch within 10 the casing. The sealing-ring 23 will be disrupted and the top plate 14 blown off before any communication is opened between the chamber 20 and the interior of the casing, through which the exploding gases could 15 reach the torch. The wall of the casing and the under plate 12 should be sufficiently strong to withstand the reaction of the explosion.

The casing will stand normally in an upright position under water before the torch is discharged, owing to the large air-chambers in the upper part of the casing and of the torch and the fact that the casing is anchored or weighted. When it is desired to 25 operate the torch, an electric current is sent through the cable 21 sufficient to ignite the explosive in the chamber 20, the ignition being caused by a spark or heated wire in a manner well known. The resulting explosion will blow off the cap-plate 14, disrupting 30 the sealing-strip 23. Water will quickly enter the opening 16 and float the torch *a*, which is sufficiently buoyant to lift the plate 12 from the casing. Water will enter the 35 openings 8 and cause acetylene gas to be discharged from the burners and will also enter the opening in the bottom of the phosphid-chamber 4, causing phosphoreted hydrogen to be discharged from the tube 5. The 40 latter gas igniting on contact with the atmosphere will immediately ignite the acetylene gas issuing from the burners, and a brilliant flame, which is practically inextinguishable, will be produced so long as the 45 carbid of calcium lasts.

Having described our invention, what we claim, and desire to secure by Letters Patent, is—

1. The combination of a buoyant torch, a 50 water-tight casing within which said torch is contained, and means for automatically opening said casing and releasing the torch while the casing is under water.

2. The combination with a buoyant torch, of a water-tight casing within which said torch is contained, means for anchoring the casing under water, and means for automatically opening the casing and discharging the torch while the casing is under water. 55

3. The combination with a buoyant torch, of a water-tight casing within which the torch is contained, means for anchoring said casing under water, means for opening the casing while under water to discharge the torch and a flexible connection between the casing and the torch whereby the torch will be prevented from drifting after it reaches the surface. 60

4. The combination with a buoyant torch, provided with an illuminating material and an igniter, of a casing within which the torch is hermetically sealed, a charge of explosive material arranged to blow off the top of said casing when ignited, and means for igniting said explosive. 70

5. The combination with a buoyant torch, of a casing surrounding the torch, two interlocking plates forming the top of said casing, a chamber between said plates charged with explosive material, and means for igniting said explosive. 75

6. The combination with a buoyant torch, of the casing surrounding the torch, the plate resting on top of the casing and provided with a series of openings, the top plate provided with projections entering said openings, the 85 chamber between said plates charged with explosive material and means for igniting said material.

7. The combination with a buoyant torch charged with carbid of calcium and having 90 an igniter charged with phosphid of calcium, of a closed casing within which said torch is contained, means for anchoring the casing, and means for automatically opening the casing to liberate the torch. 95

In testimony whereof we affix our signatures each in presence of two witnesses.
